CLAIM

The ornamental design for a light fixture, as shown and described.

DESCRIPTION

FIG. 1 is a front and left side perspective view of a light fixture showing our new design;

FIG. 2 is a front and right side perspective view thereof;

FIG. 3 is a second embodiment of FIG. 1, the only difference being the configuration of the lens;

FIG. 4 is a second embodiment of FIG. 2, the only difference being the configuration of the lens;

FIG. 5 is a third embodiment of FIG. 1, the only difference being the configuration of the lens;

FIG. 6 is a third embodiment of FIG. 2, the only difference being the configuration of the lens;

FIG. 7 is a back and left side perspective view thereof;

FIG. 8 is a back and right side perspective view thereof;

FIG. 9 is a front side view thereof;

FIG. 10 is a back side view thereof;

FIG. 11 is a left side view thereof;

FIG. 12 is a right side view thereof;

FIG. 13 is a top view thereof; and,

FIG. 14 is a bottom view thereof.

The broken lines in the drawings illustrate environmental subject matter only and form no part of the claimed design.
